UNITED STATES PATENT OFFICE.

GEORGE P. TILTON, OF NEWBURYPORT, MASSACHUSETTS, ASSIGNOR TO
THE TOWLE MANUFACTURING COMPANY, OF SAME PLACE.

DESIGN FOR A SPOON, &c.

SPECIFICATION forming part of Design No. 21,566, dated May 24, 1892.

Application filed April 16, 1892. Serial No. 429,482. Term of patent 7 years.

To all whom it may concern:

Be it known that I, GEORGE P. TILTON, of Newburyport, in the county of Essex and State of Massachusetts, have invented and produced 5 a new and original Design for the Handles of Spoons, Forks, Knives, &c., of which the following is a specification.

Reference is to be had to the accompanying drawings, in which Figures 1 and 2 represent, 10 respectively, the obverse and reverse of a spoon embodying my new design.

The design, which consists of the massed ornamentation shown, is distinguished by its general effect, and the drawings are mainly 15 relied on to elucidate its novel features, the following general description being given for the purpose of this specification.

The ornamentation on the front of the spoon is massed on the handle throughout the length 20 of the same except near the outer end, where a plain panel *a* appears, bordered at the sides by oppositely-curved scrolls *b*. The massed ornamentation is made up of purely conventional scrolls, conventionalized stems of forget-me-nots, and the flowers of the latter. The scrolls appear as if intertwined and the members thereof are generally in multiple. Thus 25 at the end beyond the panel *a* the several members *c* range in a generally diagonal direction and are inturned at their terminals, a succession of such inturned terminals appear-

ing at one edge at the end, as at *c'*. At the base of the figure formed by the members *c* a fern-like figure *d* appears. Below the panel *a* the massed scrolls *e'* and conventionalized stems and leaves *e*² or certain members thereof are curved in the direction of and crossed by each other at intervals and join the side borders of the panel *a*. The flowers of the forget-me-nots *e* are interspersed throughout the scroll figures. The ornamentation on the reverse of the handle is made up of the substantially continuous edge beads *ff'* of changing curves and the foliate scrolls *g g'*, which latter form, respectively, the top and bottom of 40 the framing of a plain panel *h*, of which the beads *ff'* form the sides. At the extreme end the beaded edge *f*² is in the form of irregular scalloping, the detail members of the scroll-like figure *g* being curved into conformity 45 with such scallops.

I claim—

1. The design for the handles of spoons and similar articles, as herein shown and described.
2. In a design for the handles of spoons, &c., 55 the obverse thereof, as shown and described.
3. In a design for the handles of spoons, &c., the reverse thereof, as shown and described.

GEORGE P. TILTON.
